UNITED STATES PATENT OFFICE.

JAMES D. S. REED, OF CHICAGO, ILLINOIS.

ELECTRIC HEATER.

SPECIFICATION forming part of Letters Patent No. 622,166, dated March 28, 1899.

Application filed March 25, 1898. Serial No. 675,090. (No model.)

To all whom it may concern:

Be it known that I, JAMES D. S. REED, of Chicago, in the county of Cook and State of Illinois, have invented certain new and useful 5 Improvements in Electric Heating Apparatus; and I do hereby declare that the following is a full, clear, and exact description thereof, reference being had to the accompanying drawings, and to the letters of reference 10 marked thereon, which form a part of this specification.

This invention relates to improvements in electrical heating apparatus; and the object of the invention is to produce a cheap and 15 simple construction in devices of this character designed to be used for heating apartments, street or railway cars, and other like places where a heating-stove is required.

The invention consists in the matters hereinafter set forth, and more particularly pointed out in the appended claims.

In the drawings, Figure 1 is a side elevation of an apparatus embodying my invention. Fig. 2 is a longitudinal section thereof. Fig. 25 3 is a top plan view of the same. Fig. 4 is a side elevation of the inner core, showing a part of the wiring thereon.

As shown in said drawings, A designates the outer casing of the apparatus, which may 30 consist of any suitable radiating material—such as iron, glass, porcelain, or the like—which is supported upon suitable legs or standards A'. Said casing is provided at its upper end with a removable cover A², by means of 35 which the active parts of the apparatus may be inserted therein. In order to provide a greater surface for radiation, the outer surface of said casing is corrugated. Said casing is herein shown as cylindrical in form, but obviously 40 may be made of any cross-sectional form found convenient or desirable.

B designates a core located within the interior of the hollow casing A and of less exterior diameter than the interior diameter of 45 the said casing. Said core B is supported at its lower end upon an inwardly-extending flange A³ in the lower interior of the casing. Said core is herein shown and will preferably be made of hollow construction, but may, if 50 desired, be made solid. Said core is provided on its periphery with a continuous spiral groove b, which extends from the lower to the

upper end thereof. Within this groove is located a continuous conducting-wire C. Said core will be made of any suitable insulating 55 material and will preferably be made of a material which is a good conductor of heat as well, such as porcelain or like composition. The groove b within the outer face of the core will be of such depth as to hold the wire permanently in place in the core and to insulate the several turns of wire from each other.

C' designates a lead-wire which leads from any suitable source of current-supply. The return or ground wire C² leads from the upper end of the core back to the lower end thereof and, as herein shown, extends through an opening in the upper wall of the hollow core and downwardly through the hollow interior thereof. With this construction when 65 the winding C is thrown into the circuit of a current having a relatively high potential the resistance of the winding to said current will cause the same to become heated in a well-known manner, thereby heating by conduction the exterior of the casing A, as well as the 70 enveloped core B. The entire length of the winding will be raised to the same temperature, and the apparatus will give out heat to its greatest capacity.

A⁶ designates an insulating-lining upon the inner surface of the casing A and between the same and the winding C.

D D' designate a switch which is connected with the return-wire and which is adapted to 85 cut a portion of the resistance-coil out of circuit when desired. The rod D is provided with a plurality of enlargements d, through which the screw-plugs D' pass, which latter have screw-threaded engagement with the 90 outer casing and are adapted to have contact at their inner ends with the coil.

The casing A is herein shown as provided with a plurality of apertures within which are located insulating-plugs E, which are provided on their inner ends with heads E', which serve to separate the winding C from the inner lining A⁶ of the casing A and also center the core within the casing. Said plugs E may be made of glass or other insulating material. 95 The upper wall or lid of the casing is provided with a plurality of openings a, which serve to transmit the heat from the interior of the core in a well-known manner. The lower

end of said core is provided with an opening A⁴, which acts in connection with said openings a in the upper wall or lid A² to allow the passage of air through the heated interior of the core, thereby increasing the heating capacity of the apparatus as a whole. Such construction also aids in directing the heat to where it can be utilized as a means for heating cooking utensils placed upon the top of the apparatus. Obviously the hollow interior of the core may be provided with one or a number of inner cores, which may be connected to the winding C in any preferred manner.

15 I claim as my invention---

1. An electrical heating apparatus comprising an outer casing, an inner tubular core of non-conducting material having a spiral groove upon its outer surface, a wire forming 20 at one end a supply-wire and at its other end a return-wire and wound between its ends about the core in the said groove from one end of the said core to the other, the several turns of the said wire upon the core being in-

sulated from each other, and the said outer 25 casing being provided with a plurality of non-conducting inwardly-extending projections interposed between the said outer casing and the winding on the said core.

2. An electrical heating apparatus comprising 30 an outer casing, an inner core, a wire forming at one end a supply-wire and at its other end a return-wire and wound between its ends about the core from one end thereof to the other, the several turns of said wire upon 35 the core being insulated from each other and a plurality of insulating-plugs mounted in said casing and provided on their inner ends with heads which are interposed between said outer casing and the winding upon the core. 40

In testimony that I claim the foregoing as my invention I affix my signature, in presence of two witnesses, this 21st day of March, A. D. 1898.

JAMES D. S. REED.
